MEANS FOR CONTROLLING WELL FLOW

Samuel F. Cunningham, Oklahoma City, Okla., assignor of one-half to Brauer Machine & Supply Company, Oklahoma City, Okla., a corporation of Oklahoma

Application November 16, 1938, Serial No. 240,848

11 Claims. (Cl. 251—129)

This invention relates to improvements in flow beans for oil wells, and more particularly to a bottom-hole flow control device for regulating the amount of oil which may flow from a well, so as to comply with pro-ration laws and the like.

One of the objects of the invention is to provide an adjustable flow bean which, although arranged in the well and not directly connected to means extending to the surface of the well, may be controlled by the actuation of a cut-off valve at the surface or upper end of the well.

Another object is to supply a bottom hole adjustable flow bean of relatively simple inexpensive and practical construction, and one that is not liable to get out of order in operation.

Further objects of my invention are to produce an adjustable flow bean which will be self-lubricated and automatically balanced, and of such a structure as will enable its economical production and a high degree of efficiency and durability in operation.

Having now indicated, in a general way, the nature and purpose of my invention, I will proceed to a detail description thereof, with reference to the accompanying drawings, in which I have illustrated a preferred embodiment, and in which,

Fig. 1 is a vertical sectional view partly in elevation, of my improved flow bean, with the valve or active member of the same shown in a descending position.

Fig. 2 is a similar view of the upper portion of the structure, with the valve in its uppermost position.

Figure 3 is a like view of the lower portion of the structure, with the valve in its lowermost position.

Figs. 4, 5, 6 and 7 are horizontal sectional views taken respectively on the lines 4—4, 5—5, 6—6 and 7—7 of Fig. 1.

Referring to the drawings, 8 designates a sleeve or barrel, preferably provided at its end portions with internal threads for engagement with external threads of an upper end member 9, and a lower member 10. Each of these members preferably has internal threads for use in attaching the structure to a tubing string or the like.

The portion 11 of the member 9 which extends into the sleeve, is provided at its bottom with valve seats 12, 13, 14 and 15, best shown in Fig. 4, which are spaced ninety degrees apart. Immediately above the seats 12, 13 and 14, the part 11 is provided with ports 16, 17 and 18 of gradually increasing diameter, the port 16 being smallest,

and the port 18 the largest. The part 11 is solid above the seat 16, as indicated at 19.

A skirt depends from the part 11 and forms cam teeth 20, each of which extends 90°, and has a vertical edge 21 and a curved edge 22, the latter being 90° in length.

An active member or valve 23 is arranged to reciprocate in the barrel, and consists of a cylindrical body 24 provided with a series of bores 25 and 26 (see Figs. 5 and 6), each of which extends vertically therethrough. These bores may all be of the same size, and they are spaced apart 90° from one another, so as to register with the valve seats 12, 13, 14, and 15. The port 25 is unobstructed, but the ports 26 are obstructed. They are provided at their upper ends with retained auxiliary valves or balls 27 adapted, when the valve 23 is in its uppermost position, to cooperate with three of the seats of the part 11 so as to close at least two of the ports 16, 17, 18, while permitting flow through the other one of said ports, or for completely closing the flow through all three ports 16, 17 and 18.

Each ball is yieldingly urged upward by a spring 28 arranged in its port 26, and such springs are retained in their ports by a disk or plate 29 that is secured to the bottom of the valve member 23 by any suitable means such as a screw 30. This arrangement allows cleaning or replacement, and the removal of sand in the event sand should enter the ports 26.

The cylinder 24 is arranged in a cam sleeve 31 which is coaxial with the skirt of the member 11, and is provided at its upper end with cam teeth 32, each of which has a vertical edge 33 and a cam edge 34, the latter extending 90°. Such teeth cooperate with the teeth 20, as will be hereinafter explained.

The lower end of the cam sleeve terminates in teeth 35 which are similar to the teeth of the part 11, with the exception that the curved surfaces 36 of the teeth 35 extend upwardly in a counter-clockwise direction, while the edges 32 of the teeth 20 extend upward in a clockwise direction. It is also to be noted that the vertical edges 37 of the teeth 35 are displaced 45° relatively to the vertical edges 33 of the teeth 32.

The member 10 at the bottom of the barrel 8 is tubular and provided at its upper end with upwardly extending teeth 38 which are complementary to the teeth 35, and have vertical edges 39 which are in alignment with the vertical edges 21 of the teeth 20.

In operation, such structure may be employed to regulate the flow from the well, and if the

valve 23 is in its uppermost position, and its port 25 is in register with the port 16, obviously, there will be a minimum flow of oil from the well. If the ports 25 and 17 are in register, greater flow will be provided, and if the ports 25 and 18 are in alignment, maximum flow will be provided. When the port 25 is in register with the valve seat 15, the balls 27 close all of the ports 16, 17 and 18, and there will be no flow through the device.

10 In order to control the device, a shut-off valve at the top of the well will be closed, and this will result in equalization of pressure at the ends of the valve 23, which will cause the valve to descend due to its own weight; it being understood, of course, that the valve is normally held in uppermost position by the pressure of the oil in the well. As the valve 23 descends, the curved edges 36 of the teeth 35 will come into engagement with the curved edges 40 of the teeth 38, and this

15 will result in rotating the valve 23 forty-five degrees, for as the valve descends, the vertical edges 37 of the teeth 35 are positioned at 45° relatively to the vertical edges 39 of the teeth 38. When the cut-off valve at the top of the well is again opened, the plunger or valve 23 will be raised, and then the edges 34 of the teeth 32 will come into engagement with the edges 22 of the teeth 20, so that the valve will be given another $\frac{1}{2}$ turn, which will bring the vertical edges 33 of

20 the teeth 32 into engagement with the vertical edges 21 of the teeth 20, so that the valve will be locked against further rotation while it is in its uppermost position.

It will be manifest that by manipulation of the cut-off valve at the top of the well, the member 23 can be turned sufficiently to permit the flow to pass through any one of the ports 16, 17 or 18, or to be entirely cut off.

While I have disclosed what I now consider to be a preferred embodiment of my invention in such manner that the same may be readily understood by those skilled in the art, I am aware that changes may be made in the details disclosed, without departing from the spirit of the invention, as expressed in the claims.

What I claim and desire to secure by Letters Patent is:

1. In a flow bean of the character described, a barrel provided with a cylindrical bore and upper outlet ports of various sizes, a cylindrical valve of substantially the same diameter as said bore arranged to reciprocate in said bore and having a port adapted to register with any one of said outlet ports, means on the valve for closing the outlet ports with which the valve port is not in register, and cooperating means in the barrel and on the valve for causing the latter to turn about the axis of the barrel due to reciprocation of the valve, whereby the valve port is shifted to register with various ones of the outlet ports.

2. In a flow bean of the character described, a barrel provided with a cylindrical bore and upper outlet ports of various sizes, a cylindrical valve of substantially the same diameter as said bore arranged to reciprocate in said bore and having a port adapted to register with any one of said outlet ports, means on the valve for closing the outlet ports with which the valve port is not in register, and cooperating means in the barrel and on the valve for causing the latter to turn about the axis of the barrel due to reciprocation of the valve, whereby the valve port is shifted to register with various ones of the outlet

ports, the first mentioned means comprising ball valves carried by the first mentioned valve.

3. In a flow bean of the character described, a barrel provided with a cylindrical bore and upper outlet ports of various sizes, a cylindrical valve of substantially the same diameter as said bore arranged to reciprocate in said bore and having a port adapted to register with any one of said outlet ports, means on the valve for closing the outlet ports with which the valve port is not in register, and cooperating means in the barrel and on the valve for causing the latter to turn about the axis of the barrel due to reciprocation of the valve, whereby the valve port is shifted to register with various ones of the outlet ports, the first mentioned means including spring pressed balls projecting from the upper surface of the valve member.

4. In a flow bean of the character described, a barrel provided with a cylindrical bore and upper outlet ports of various sizes, a cylindrical valve of substantially the same diameter as said bore, arranged to reciprocate in said bore and having a port adapted to register with any one of said outlet ports, means on the valve for closing the outlet ports with which the valve is not in register, and cooperating means in the barrel and on the valve for causing the latter to turn about the axis of the barrel due to reciprocation of the valve, whereby the valve port is shifted to register with various ones of the outlet ports, the first mentioned means including auxiliary movable valve members projecting from the upper end of the first mentioned valve.

5. In a flow bean of the character described, a barrel provided with upper outlet ports of various sizes, a valve arranged to reciprocate in said barrel and having a port adapted to register with any one of said outlet ports, means on the valve for closing the outlet ports with which the valve is not in register, and cooperating cam teeth in the barrel and at the top and bottom of the valve for causing the latter to turn about the axis of the barrel when the valve is reciprocated, whereby the valve port is shifted to register with various ones of the outlet ports.

6. In a flow bean of the character described, a barrel provided with upper outlet ports of various sizes, a valve arranged to reciprocate in said barrel and having a port adapted to register with any one of said outlet ports, means on the valve for closing the outlet ports with which the valve is not in register, and cooperating cam teeth in the barrel and at the top and bottom of the valve for causing the latter to turn about the axis of the barrel when the valve is reciprocated, whereby the valve port is shifted to register with various ones of the outlet ports, each cam tooth having one substantially vertical edge and a curved edge extending from said substantially vertical edge of one tooth to the substantially vertical edge of an adjacent tooth.

7. In a flow bean of the character described, a barrel provided with upper outlet ports of various sizes, a valve arranged to reciprocate in said barrel and having a port adapted to register with any one of said outlet ports, means on the valve for closing the outlet ports with which the valve port is not in register, and cooperating means in the barrel and on the valve for causing the latter to turn about the axis of the barrel when the valve is reciprocated, whereby the valve port is shifted to register with various ones of the outlet ports, the last mentioned means including an upper set of cam teeth arranged in the barrel.

- above the valve, a lower set of cam teeth arranged in the barrel below the valve, and upper and lower sets of cam teeth provided at opposite ends of the valve, the upper set of cam teeth of the valve being complementary to and cooperating with the upper set of cam teeth of the barrel, and the lower set of cam teeth of the valve being complementary to and cooperating with the lower set of cam teeth of the barrel.
10. 8. In a flow bean of the character described, a barrel provided with upper outlet ports of various sizes, a valve arranged to reciprocate in said barrel and having a port adapted to register with any one of said outlet ports, means on the 15 valve for closing the outlet ports with which the valve port is not in register, cooperating means in the barrel and on the valve for causing the latter to turn about the axis of the barrel due to reciprocation of the valve, whereby the valve 20 port is shifted to register with various ones of the outlet ports, and valve seats arranged at the lower ends of the outlet ports and cooperating with said first mentioned means.
9. A flow bean of the character described, 25 comprising a sleeve, an upper member connected to said sleeve and provided with a series of outlet ports of varying sizes, a set of stationary cam teeth arranged in the sleeve adjacent to said ports, a lower tubular member connected to the 30 lower end of the sleeve, a lower set of cam teeth arranged in the sleeve adjacent to said lower member, a valve arranged to reciprocate in the sleeve between said upper and lower members, and provided with sets of cam teeth complementary to said upper and lower sets of cam teeth, and adapted to cooperate with the latter to cause turning of the valve about the axis of the sleeve, due to reciprocation of the valve, a port extending through the valve and of a size substantially equal to the largest one of the outlet ports and adapted to register with any one of said outlet ports, and auxiliary valve means carried by the first mentioned valve and adapted to close said outlet ports with which the valve port is not in register when the first mentioned valve is in its uppermost position, said auxiliary valve means comprising closure elements projecting from the upper end of the first mentioned valve, springs in 25 the first mentioned valve for urging the closure elements upwardly, and means removably securing closure elements and springs to the first mentioned valve.
11. In a flow bean of the character described, 30 a barrel member provided with a cylindrical bore, a cylindrical valve member of substantially the same diameter as the bore arranged to reciprocate therein, one of said members having ports of various sizes and the other having a port adapted to register with any one of said first-mentioned ports, means on one of said members for closing the non-registering ports, and cooperating means in the barrel member and carried by the valve member for causing the latter to turn about its 35 axis due to reciprocation of the valve member, whereby the port of one member is caused to register successively with the ports of the other member.
- 45
